APPARATUS FOR ORIENTING MITERED CLEATS

David G. Kingsley, Mountain Lakes, N. J., assignor to Stapling Machines Co., Rockaway, N. J., a corporation of Delaware

Application April 9, 1952, Serial No. 281,362

13 Claims. (Cl. 198—33)

1

This invention relates to apparatus for uniformly orienting mitered-end cleats and feeding them to the conveyor bands of a box-part-making machine.

Wirebound box and crate blanks are usually formed by cleats and side material or slats stapled together to form a plurality, usually four, box sections or sides which are secured together by binding wires stapled to the box sections. The cleats are often provided with mitered ends so that when the box blank is folded around to set up the box, the abutting ends of the cleats at each corner of the box will fit snugly together to lend strength and rigidity to the box. Wirebound boxes of this general type are disclosed in U. S. Patent No. 1,933,030, issued October 31, 1933.

In wirebound box-part-making machines, properly assembled cleats and side material or slats are conveyed past a transverse row of stapling units where staples are driven astride binding wires and into the side material and cleats to form the wirebound box or crate blanks. The cleats and slats are conveyed through the machine by means of two or more conveyor bands on which are secured spacer blocks having projecting push-elements which engage the slats and the cleats and convey them in properly assembled relationship. In the copending application Serial No. 70,868, apparatus for automatically feeding cleats to the conveyor bands of a box-part-making machine is disclosed. This apparatus includes a hopper in which a generally vertical stack of cleats is held in position above each of the conveyor bands, with the bottom cleat of the stack in the path of the cleat-pushing elements on the spacer blocks so that the elements will engage and push the cleats individually and successively from the bottom of the stack. This apparatus enables a considerable saving of time and effort on the part of the personnel employed in placing the box materials on the conveyor bands of the machine. However, the apparatus disclosed necessitates prearrangement of the cleats to give them uniform orientation.

The present invention has for its objectives the provision of practical, reliable and economical apparatus for uniformly orienting mitered-end cleats so that they may be fed automatically to the conveyor bands of a box-part-making machine, thereby making possible a substantial saving in the time and effort required of the personnel who tend the machine, and enabling

2

substantial savings in the cost of producing box parts or box blanks.

The apparatus of the invention includes a cleat hopper in which the cleats are stacked generally parallel to each other but without regard to orientation. A pickup conveyor is movable across the bottom of the hopper to remove cleats from the hopper and convey them single file along a path generally lateral to the cleats. The cleats are carried against the periphery of a pair of rotatable spacing wheels having peripherally spaced elements for engaging the cleats and removing them individually and at timed intervals from the pickup conveyor. This results in spacing the cleats apart so that there is sufficient room to permit axial rotation of the cleats to achieve uniform orientation.

The spacing wheels deliver the cleats to a pair of cleat orienting belts which are spaced apart a distance approximately equal to the length of the cleats and are arranged to convey the cleats along a path generally perpendicular to the long axes of the cleats by engagement of the orienting belts with the ends of the cleats. The orienting belts are inclined so as to present to the end of the cleats surfaces inclined upwardly and outwardly so that the cleats in a short-side-up position ride on the orienting belts at a higher level than the cleats in a short-side-down position.

A pair of cleat turning members or pawls are mounted above the cleat orienting belts in position to engage and impede forward movement of the upper portions of the cleats riding on the orienting belts in a short-side-up position, but not to engage the cleats riding in a short-side-down position. These cleat turning members, acting in conjunction with frictional engagement of the lower corners of the cleats with the moving orienting belts, create a couple which rotates the cleats and causes them to fall to a short-side-down position. A pair of leaf springs is mounted adjacent the cleat turning members in position to engage and bear downwardly upon the trailing portion of the upwardly facing short side of each of the cleats in a short-side-up position on the orienting belts, to enhance this rotative couple.

In order to place all of the cleats in the desired orientation prior to feeding them into the hoppers above the conveyor bands of the box-part-making machine, all of the cleats are given an additional 90° rotation. This is accomplished on a stacking conveyor which is positioned to receive the cleats at the output end of the orient-

ing belts. Cleat turning members and leaf springs, similar to those previously described, are positioned above the stacking conveyor for engaging all of the cleats thereon and rotating them through an angle of 90°.

The rate at which the cleat orienting apparatus tends to supply cleats into each of the hoppers above the conveyor bands exceeds the rate at which the cleats are removed from the hoppers by the conveyor bands. Accordingly, after a brief period of operation, a solid line of cleats will accumulate on the stacking conveyor, with the stacking conveyor continuing to run and sliding frictionally under the cleats. In order to disengage the drive to the pickup conveyor, spacing wheels and cleat orienting belts when a solid line of cleats of predetermined extent has accumulated on the stacking conveyor, a pair of photoelectric cells are positioned at spaced points along the path of the cleats on the stacking conveyor and a pair of light sources are arranged in line with the photoelectric cells on the opposite side of the cleat path. These photoelectric cells are connected to an electrically controlled clutch and brake in the drive to the pickup conveyor, spacing wheels and cleat orienting belts in such manner that when the beams of light to both of the photoelectric cells have been intercepted by cleats on the stacking conveyor, the clutch is disengaged and the brake is applied to stop the drive to these units until sufficient cleats have been removed to expose both light sources.

In the drawings, in which an illustrative embodiment of the invention is shown:

Figure 1 is a somewhat diagrammatic side elevational view of a dispensing apparatus embodying features of the invention, the apparatus being shown partly in section;

Figure 2 is a somewhat diagrammatic top plan view of the machine;

Figure 3 is a fragmentary vertical section, at enlarged scale, taken generally along the line 3—3 of Figure 1;

Figures 4, 5 and 6 are diagrammatic views of one of the cleat-turning assemblies of the apparatus showing, in successive steps, the turning of a cleat by said assembly; and,

Figure 7 is a schematic diagram of the electrical circuit which controls the drive of the apparatus.

In Figures 1 and 2, the cleat orienting and feeding apparatus is shown positioned alongside one of the conveyor bands 18 (at the extreme right in those figures) near the input end of the box-part-making machine. The various component mechanisms of the apparatus are supported on a framework which includes a plurality of upright members 12, with appropriate longitudinal and transverse bracing members, mounting brackets and bearings for the various components of the apparatus.

The apparatus includes a large hopper 14, shown at the extreme left in Figure 1, which is adapted to receive a plurality of cleats 13 arranged generally parallel to each other but without regard to orientation. The hopper 14 is open at its lower end and a pair of pickup conveyor belts 16 are arranged to extend across the bottom of the hopper along a line generally perpendicular to the long axes of the cleats in the hopper. The pickup conveyor belts 16 are trained upon idler pulleys 13 and drive pulleys 19, the latter being driven from a motor 20, suitably supported near the floor beneath the center of the apparatus.

The drive from the motor 20 to the pulleys 19

is through a pulley 21 (Figure 1) on the motor shaft, a V-belt 22, and a pulley 23 (Figure 2) fixed near one end of a sleeve 24 rotatably supported on a fixed shaft 25 which is supported at either end by brackets 31 on a cross-beam 33 of the frame of the apparatus. One plate of a solenoid-controlled clutch 26 is fixed on the other end of the sleeve 24, and the other plate of the clutch 26 is fixed at one end of a second sleeve 28 also rotatably mounted on the fixed shaft 25. A sprocket 29 on the sleeve 23 has trained about it a chain 30 which is also trained about a sprocket 32 secured on the same shaft 24 on which the pulleys 19 are fixed. Arranged to act upon the opposite end of the sleeve 28 is a solenoid-controlled brake 27, which is operable, in combination with the clutch 26, to control the drive train just referred to, as will be more particularly described hereinafter.

The pickup conveyor belts 16 are thus driven across the bottom of the hopper 14 in the direction indicated by the arrow A in Figure 1, and tend to move the cleats out of the hopper in that direction. The lower end 14a of the wall of the hopper 14 toward which the pickup conveyor belts 16 tend to move the cleats out of the hopper is spaced above the pickup conveyor belts 16 by a distance slightly exceeding the thickness of the cleats so as to permit the cleats to move from the hopper only single file on the conveyor belts 16.

A pair of spacing wheels 36 are positioned across the output or right-hand end of the pickup conveyor belts 16, as viewed in Figures 1 and 2, so that the belts 16 carry the cleats laterally against the periphery of the spacing wheels 36. The spacing wheels 36 are secured to a rotatable shaft 38 which is driven in the direction indicated by the arrow B in Figure 1, by means of a sprocket 40, which is coupled through a chain 42 to a sprocket 44 (Figure 2) fixed on the driven shaft 34 previously referred to.

Around the periphery of each of the spacing wheels 36 are provided a plurality of equally spaced, radially projecting cleat-engaging elements 36a adapted to engage the cleats on the pickup conveyor belts 16 and lift them from the belts and over the tops of the spacing wheels 36.

The drive ratio of the pickup conveyor belts 16 and spacing wheels 36 is such that the pickup conveyor belts 16 will furnish cleats to the spacing wheels 36 at a rate faster than the rate at which the spacing wheels remove cleats from the pickup conveyor belts. This causes cleats to accumulate on the pickup conveyor belts 16, as shown in Figures 1 and 2. Since there is only frictional engagement between the pickup conveyor belts 16 and the cleats thereon, as cleats accumulate in a solid line on the pickup conveyor belts, the belts will simply slide frictionally under the bottom surfaces of the cleats. The cleats will be moved forward intermittently, being stationary except when the cleat engaging elements 36a on the spacing wheels 36 remove a cleat from the output end of the pickup conveyor belts 16, at which time the line of cleats on the pickup conveyor belt will move forward a distance equal to the thickness of one cleat to fill the space vacated by the cleat removed and place the next cleat in position to be picked up by the next succeeding pair of elements 36a on the spacing wheels 36.

A pair of inclined slide rails 46 are mounted at the output or right-hand end of the spacing wheels 36, as viewed in Figures 1 and 2, to re-

ceive the cleats from the spacing wheels 36. The left-hand ends of the slide rails 46 are elevated above their right-hand ends and are positioned so as to intersect the peripheral line of the spacing wheels 36 at a point just to the right of the tops of the spacing wheels, so that as the cleats pass over the tops of the spacing wheels 36 they are picked up by the slide rails 46 and slide down them onto a pair of orienting belts 48.

The function of the foregoing mechanism is thus to supply cleats to the cleat orienting belts 48 at spaced intervals. This prevents the accumulation of a solid line of cleats on the cleat orienting belts and allows room for rotating the cleats to achieve uniform orientation.

The orienting belts 48 are spaced apart a distance approximately equal to the length of the cleats and are adapted to convey the cleats along a path generally perpendicular to the long axes of the cleats by frictional engagement with the ends of the cleats. The orienting belts are trained upon idler pulleys 50, which are mounted on short, rotatable shafts 52, and about drive pulleys 54, which are secured to short, rotatable drive shafts 56 (see also Figure 3). The axes of the shafts 52 and 56 are at 45° angles with respect to the horizontal (as best shown in Figure 3) so that the pulleys 50 and 54 and orienting belts 48 are inclined to present to the ends of the cleats surfaces inclined upwardly and outwardly; thus, the cleats which fall on the belts in a short-side-up position (as shown in broken lines in Figure 3) ride at a higher level than the cleats which fall onto the belts in a short-side-down position (as shown in full lines). Because of the shape of the ends of the cleats, and of the inclination of the orienting belts 48, the cleats fall to either one or the other of these two positions.

The drive shafts 56 for the cleat orienting belts 48 are rotatably supported in bearings 57 (Figure 3) mounted on brackets 53 secured to upper ends of two of the upright members 12. The shafts 56 are driven through bevel gears 59 and 60, the latter being secured at opposite ends of a short, horizontal drive shaft 62 rotatably supported in bearings 64 on a base 66 secured on a cross-brace 67 of the frame of the apparatus. The drive shaft 62 has keyed thereon a spur gear 68 which meshes with a spur gear 70 (Figure 2) on a shaft 72 which extends transversely of the apparatus and is rotatably supported at its opposite ends in bearings 74 (Figure 2). The latter shaft 72 has keyed thereon a sprocket 76 about which is trained a chain 78 which is also trained about a sprocket 80 on the driven shaft 38 previously referred to. It is thus apparent that the cleat orienting belts, as well as the spacing wheels 36 and pickup conveyor belts 16 are driven by the motor 29 through the solenoid-actuated clutch 26 (Figure 2).

A pair of cleat turning members or pawls 82 are rotatably mounted above the cleat orienting belts 48 on a shaft 84 which extends transversely of the apparatus and is supported at its opposite ends on upstanding brackets 86.

The rotatably mounted pawls 82 are normally urged by their own weight in a clockwise direction about the shaft 84, as viewed in Figures 4, 5 and 6. This movement is limited by means of stop fingers 88 which extend beneath the pawls 82 and are adjustably secured on transverse shaft 54 by means of collars 90 (Figure 2). The collars 90 and stop fingers 88 are so positioned that the stop fingers cause the cleat turning members 75

or pawls 82 to assume a normal position wherein their lower ends 82a are at such level as to engage the upper portions of the cleats riding on the orienting belts 48 in a short-side-up position, but not the cleats in a short-side-down position.

In Figure 4, a cleat 13, in a short-side-up position, is shown as it first engages one of the pawls 82. The forward movement of the upper portion 10 of the cleat is impeded by the pawl 82, while the lower portion of the cleat tends to move in the direction of the arrow C, due to frictional engagement between the lower corners of the cleat and the moving belts 48. This creates a rotative couple which tends to turn the cleat about its long axis in a counterclockwise direction, as indicated by the arrow D. This rotative couple is enhanced by means of leaf springs 92 which are fixed at one end to the transverse shaft 84 alongside the pawls 82 and have their opposite ends 92a positioned to engage and press downwardly upon the after portion of the upper surface of the cleats in a short-side-up position, when these cleats reach the point of engagement with pawls 82. This rotative couple causes the cleats to turn in a counterclockwise direction, as shown in Figures 5 and 6.

The rotatable mounting of the pawls 82 permits the pawls to move upward yieldingly, as shown in Figures 5 and 6, to permit the cleats to pass between the pawls 82 and the orienting belts 48, while the cleats are rotating.

As will be understood from an examination of Figure 6, the action of the pawls 82 is only such as to rotate the cleats through an angle of approximately 90° or slightly more; however, the cleats will ride only in either a short-side-up or a short-side-down position and since the cleats halfway between these two positions are urged by gravity toward a short-side-down position and since the pawls have initiated rotation of the cleats to a short-side-down position and continue to engage the cleats to prevent a reversal of this rotation, all of the cleats fall to a short-side-down position.

The effect of the orienting elements just described is thus to position all of the cleats with their short sides down. This is the orientation in which it is desired to feed the cleats into the hopper 94 (at the extreme right in Figure 1), in which they are held in position above the conveyor bands 19 of the box-part-making machine for successive removal by the cleat-pushing elements 96a projecting from spacer blocks 96 55 clamped on the conveyor bands 19. However, it is expedient to feed the cleats into the hopper 94 through a guide channel 98 in which the cleats are rotated through a 90° angle in a clockwise direction, as viewed in Figure 1. In order to offset this rotation, means is provided to rotate the cleats through a 90° angle in the opposite direction before feeding them into the guide channel 98, as will now be described.

Adjacent the output end of the orienting belts 65 48 are a pair of stacking conveyor belts 100 which are arranged to receive cleats from the orienting belts 48 and to convey the cleats along a path generally lateral to the cleats by frictional engagement of the belts with the bottom surfaces of 70 the cleats. The transfer of cleats from the orienting belts 48 to the stacking conveyor belts is accomplished without rotation of the cleats from their short-side-down position. The stacking conveyor belts 100 are spaced apart a distance less than the length of the short sides of the

cleats and all of the cleats are thus supported at the same level on the stacking conveyor belts. The stacking conveyor belts are trained about drive pulleys 102 and large idler pulleys 103. The drive pulleys 102 are driven directly from the motor 20 through a sprocket 104 on the sleeve 24 (Figure 2), a chain 105 and a sprocket 106 on the same shaft 110 on which the pulleys 102 are fixed. The stacking conveyor belts are thus driven in the direction of the arrow E (Figure 1). At each end of the cleats on the stacking conveyor belts 100 a guide rail 113 is provided to keep the cleats in proper alignment on the belts.

Positioned above the stacking conveyor belts 100 are a pair of cleat turning members or pawls 112 which are rotatably mounted on a transverse shaft 114 supported on upstanding brackets 116. Associated with each of the cleat turning pawls 112 are a stop finger 118 and a leaf spring 120, which are similar in construction and arrangement to the corresponding elements associated with pawls 82 previously described. The operation of the pawls, stop members and springs is similar to that previously described, except that the lower ends of the pawls 112 are positioned to engage and impede forward movement of the upper portions of each of the cleats on the stacking conveyor belts 100, so that each cleat will be subjected to a rotative couple which will turn the cleat through an angle of 90° in a counter-clockwise direction, as viewed in Figure 1. Thus, as may be seen in the right-hand side of Figure 2, all of the cleats at the output end of the stacking conveyor belts 100 are oriented with their short sides forward, so that the 90° clockwise rotation imparted to the cleats in the guide channel 98 will again place the cleats in a short-side-down position as they enter the hopper 94.

The speed of the stacking conveyor belts 100, and of the other conveying mechanisms, is such that cleats will be supplied into the hopper 94 at a rate in excess of the rate at which they are removed from the hopper by the cleat pushing elements 96a on the conveyor bands 10. This causes cleats to accumulate in the hopper 94 and on the stacking conveyor belts 100, with the stacking conveyor belts sliding frictionally under the cleats, and maintaining the cleats in a closely abutting column. Means is provided to shut off the supply of cleats to the stacking conveyor belts when this continuous line of cleats reaches a predetermined length.

To this end, a pair of suitable light sources 122 and 123, for example, electric lamps with condensing lenses, are positioned at spaced points beneath the path of the cleats on the stacking conveyor belts 100 and arranged to direct beams of light upwardly through the cleat path to a pair of photoelectric cells 124 and 125 which are mounted above on overhead frames 128.

The photoelectric cells 124 and 125 are electrically connected to control the clutch 26 and brake 27 so that when the beams of light to both of the photoelectric cells are intercepted by cleats on the stacking conveyor belts 100, which means that there is a solid line of cleats on the stacking conveyor belts extending to the point where the beam of light from the left-hand light source 122 (as viewed in Figures 1 and 2) intersects the path of the cleats, the clutch 26 is disengaged and the brake 27 is applied to stop the pickup conveyor belts 16, the spacing wheels 36 and the orienting belts 48, and thereby stop the supply of cleats to the stacking conveyor belts 100. Since the stacking conveyor belts 100 are

connected directly to the motor 20 and are not affected by the disengagement of the clutch 26, the stacking conveyor belts 100 will continue to convey cleats into the hopper 94 for removal by the cleat pushing elements 96a on the conveyor bands 10. However, no more cleats will be supplied to the stacking conveyor belts 100 until the solid line of cleats thereon has moved forward to such extent that the beams of light to both of the photoelectric cells 124 and 125 are uncovered.

The lamps 122 and 123 and photoelectric cells 124 and 125 are so positioned that the beams of light are directed through the path of the cleats at an oblique angle relative to the sides of the cleats, so that when two abutting cleats intercept one of the beams of light, no appreciable amount of light reaches the photoelectric cell. The width of each of the beams of light is greater than the effective width of a single cleat, as viewed from the oblique angle at which the beams of light intersect the cleat path, so that neither of the beams of light can be entirely extinguished by one cleat alone. Thus, a solid line of cleats, and, in practical effect, nothing less, will actuate the control circuit to shut off the supply of cleats.

Figure 7 schematically illustrates the electrical interconnection between the photoelectric cells 124 and 125 and the clutch 26 and brake 27. As may be seen in that figure, the photoelectric cells 124 and 125 are respectively connected in series with the windings 128a and 130a of a pair of control relays 128 and 130 across the lines 132 and 134, which are connected to the opposite terminals of the source of electrical power. The contacts 128b of the relay 128 are normally closed and are connected by means of conductors 135 and 136 between one of the power lines 132 and one side of the winding 142a of a triple-pole power relay 142. The opposite terminal of the winding 142a is connected through the normally closed contacts 130b of the other control relay 130 and the conductor 140 to the other power line 134. The normally open contacts 142b of the power relay 142 are connected in series with the solenoid 27a which controls the brake 27, across the power lines 132 and 134, while the normally closed contacts 142c are connected in series with the solenoid 26a which controls the clutch 26, across the power lines 132 and 134. The normally open contacts 142d of power relay 142 are connected in parallel with the contacts 128b of control relay 128 to serve as holding contacts for the power relay 128, as will subsequently be described.

The functioning of this circuit is as follows: When the operation of the apparatus is first commenced, there are of course no cleats on the stacking conveyor belts 100, so that light from the lamps 122 and 123 reaches both of the photoelectric cells 124 and 125, respectively. Thus, both of the photoelectric cells 124 and 125 are electrically conductive, so that current flows from the power lines 132 and 134 through the photoelectric cells 124 and 125 and through the windings 128a and 130a of the control relays 128 and 130, to maintain both control relays energized and keep their normally closed contacts 128b and 130b open.

As operation of the apparatus continues, due to the fact that the apparatus tends to supply cleats into the hopper 94 at a rate faster than the rate at which they are removed from the hopper, cleats will accumulate on the stacking conveyor belts 100 until the beam of light to the right-

hand photoelectric cell 125 is intercepted. This will render the photoelectric cell 125 nonconductive and de-energize the relay 130, allowing its normally closed contacts 130b to close and connecting one side of the winding 142a of the control relay 142 to the power line 134. This will not affect the operation of the apparatus until the continuous line of cleats on the stacking conveyor belts 100 becomes of such extent that the beam of light to the left-hand photoelectric cell 124 is also intercepted. When this happens, the photoelectric cell 124 will become nonconductive and control relay 128 will be de-energized, allowing its contacts 128b to close and connect the opposite terminal of the winding 142a of control relay 142 to the other power line 132. This will energize the control relay 142, opening its normally closed contacts 142c to de-energize clutch solenoid 26a and disengage the clutch 26. The energization of power relay 142 will also close its normally open contacts 142b, energizing brake solenoid 27a and applying the brake 27 to stop the movement of the pickup conveyor belts 16, spacing wheels 36 and orienting belts 48. It will also close the holding contacts 142d of the power relay 142.

The supply of cleats to the stacking conveyor belts 100 will thus be cut off. The stacking conveyor belts, however, being driven directly from the motor 20, as previously described, will continue to run and to supply the accumulated cleats into the hopper 94. As the cleats are removed from the bottom of the hopper by the cleat pushing elements 96a, the accumulated cleats will be moved forwardly to uncover the beam of light to the left-hand photoelectric cell 124. This will render the photoelectric cell 124 conductive and again energize the control relay 128 and open its contacts 128b. However, since the holding contacts 142d of the power relay 142, which are now closed by the energization of power relay 142, are connected in parallel with the contacts 128b of control relay 128, the re-energization of relay 128 alone will not affect the operation of the apparatus. When the stack of cleats on the stacking conveyor belts 100 has diminished sufficiently to uncover the beam of light to the right-hand photoelectric cell 125, the photoelectric cell 125 will be made conductive and the control relay 120 will be re-energized to open its contacts 130b and disconnect the other end of the winding 142a of the power relay 142 from the power line 134. This will de-energize the power relay, opening its contacts 142b to de-energize brake solenoid 27a and release the brake 27, and closing its contacts 142c to energize clutch solenoid 26a and engage the clutch 26 to resume the drive of the pickup conveyor belts 16, spacing wheels 36 and orienting belts 48. This cycle of intermittent operation will be repeated so as to keep cleats supplied to the hopper 94, without accumulating an excessive number of cleats on the stacking conveyor belts 100.

While apparatus has been shown for feeding cleats to only one of the conveyor bands of the box-part-making machine, it will be appreciated that the feed of cleats to the other conveyor band may be accomplished similarly, either by duplicate orienting apparatus, or by dividing the supply of oriented cleats equally between the two conveyor bands. Where cleats of two different lengths are to be fed to the conveyor bands of the machine, as where boxes with oblong ends are being made, the two lengths of cleats may be oriented separately and fed into separate hop-

pers above each of the conveyor bands or intermixed alternately and fed into special hoppers designed for the feeding of two lengths of cleats.

It will therefore be appreciated that the present invention provides practical means for uniformly orienting mitered cleats preparatory for feeding them to the conveyor bands of a box-part-making machine. Thus it may be seen that the aforementioned as well as other desirable objects have been achieved. However, it should be emphasized that the particular embodiments of the apparatus shown and described herein are intended as merely illustrative and not as restrictive of the invention.

15. I claim:

1. Apparatus for uniformly orienting mitered-end cleats preparatory for feeding said cleats to a box-part-making machine, said apparatus comprising cleat orienting elements spaced apart a distance approximately equal to the length of said cleats and having surfaces adapted to engage the opposite ends of said cleats for supporting said cleats, said surfaces being so shaped that the cleats in a short-side-up position on said cleat orienting elements are supported at a different level than the cleats in a short-side-down position, a cleat turning member positioned adjacent said cleat orienting elements at such level as to engage and impede relative movement of the cleats in one of said positions on said orienting elements but not the cleats in the other of said positions, and means to cause relative movement between said cleat orienting elements and said cleat turning member to cause engagement between said cleat turning member and the cleats in said one position to create a couple which rotates said cleats and causes them to fall to said other position.

2. Apparatus for uniformly orienting mitered-end cleats preparatory to feeding said cleats to a box-part-making machine, said apparatus comprising a pair of movable orienting belts spaced apart a distance approximately equal to the length of said cleats for receiving said cleats aligned generally parallel to each other but of different orientation and conveying said cleats along a path generally at right angles to the long axes of said cleats by engagement of said orienting belts with the ends of said cleats, said orienting belts being inclined so as to present to the ends of said cleats surfaces extending upwardly and outwardly so that the cleats in a short-side-up position ride on said orienting belts at a higher level than the cleats in a short-side-down position, and a cleat-turning member positioned above the path of said cleats at such level as to engage and impede forward movement of the upper portions of the cleats riding on said orienting belts in a short-side-up position but not the cleats riding in a short-side-down position, to create, with the moving belts, a couple which turns the former said cleats generally about said axes and causes them to fall to a short-side-down position.

3. Apparatus as claimed in claim 2 wherein said cleat turning member is mounted for upward yielding movement to permit a cleat to pass under said cleat turning member while said cleat is rotating from a short-side-up to a short-side-down position.

4. Apparatus for uniformly orienting mitered-end cleats preparatory to feeding said cleats to a box-part-making machine, said apparatus comprising a pair of movable orienting belts spaced apart a distance approximately equal to

the length of said cleats for receiving said cleats aligned generally parallel to each other but of different orientation and conveying said cleats along a path generally at right angles to the long axes of said cleats by engagement of said orienting belts with the ends of said cleats, said orienting belts being inclined so as to present to the ends of said cleats surfaces extending upwardly and outwardly so that the cleats in a short-side-up position ride on said orienting belts at a higher level than the cleats in a short-side-down position, a cleat turning assembly positioned above and adjacent to the path of said cleats, said cleat turning assembly including a pawl arranged to engage the upper portion of the leading face of each of the cleats riding on said orienting belts in a short-side-up position, but not the cleats riding a short-side-down position, and to impede forward movement of said upper portion, and resilient means arranged to bear against the trailing portion of the upwardly facing short side of each of said cleats and to impose a downward force on said trailing portion, whereby to create, with the friction between the lower corners of said cleats and the moving orienting belts, a couple which rotates said cleats and causes them to fall to a short-side-down position, said pawl being mounted for upward yielding movement to permit a cleat to pass under said pawl while said cleat is rotating from a short-side-up to a short-side-down position.

5. Apparatus for uniformly orienting mitered-end cleats preparatory to feeding said cleats to a box-part-making machine, said apparatus comprising a hopper for holding a supply of cleats aligned generally parallel to each other but of different orientation, a movable conveyor arranged below said hopper to receive said cleats from said hopper and convey them single file to a pickup position, a rotatable spacing wheel having peripherally spaced elements for engaging said cleats at said pickup position and removing said cleats at intervals from said conveyor, a pair of movable orienting belts spaced apart a distance equal to the length of said cleats for receiving said cleats from said spacing wheel and conveying said cleats along a path generally at right angles to the long axes of said cleats, said orienting belts being inclined so as to present to the ends of said cleats surfaces extending upwardly and outwardly so that the cleats in a short-side-up position ride on said orienting belts at a higher level than the cleats in a short-side-down position, means to drive said orienting belts at a linear speed sufficient to maintain a spacing between adjacent cleats on said belts, and a cleat-turning member positioned above the path of said cleats at such level as to engage and impede forward movement of the upper portions of the cleats riding on said orienting belts in a short-side-up position but not the cleats riding in a short-side-down position, to create, with the moving belts, a couple which turns the former said cleats generally about said axes and causes them to fall to a short-side-down position.

6. Apparatus for uniformly orienting mitered-end cleats preparatory to feeding said cleats to a box-part-making machine, said apparatus comprising a hopper for holding a supply of cleats aligned generally parallel to each other but of different orientation, a movable conveyor extending across the bottom of said hopper and said hopper being arranged so that the cleats therein rest upon said conveyor with the long

axes of said cleats approximately at right angles to the direction of movement of said conveyor, and the lower end of the wall of said hopper on the side toward which said conveyor moves said cleats being spaced above said conveyor by a distance slightly greater than the thickness of one of said cleats so as to permit said cleats to move out of said hopper only single file on said conveyor, a rotatable spacing wheel extending transversely of said conveyor so that said conveyor carries said cleats laterally against the periphery of said spacing wheel, said spacing wheel having peripherally spaced elements for engaging said cleats and lifting them at intervals from said conveyor, a pair of movable orienting belts spaced apart a distance equal to the length of said cleats for receiving said cleats from said spacing wheel and conveying said cleats along a path generally at right angles to the long axes of said cleats, said orienting belts being inclined so as to present to the ends of said cleats surfaces extending upwardly and outwardly so that the cleats in a short-side-up position ride on said orienting belts at a higher level than the cleats in a short-side-down position, and a cleat-turning member positioned above the path of said cleats at such level as to engage and impede forward movement of the upper portions of the cleats riding on said orienting belts in a short-side-up position but not the cleats riding in a short-side-down position, to create, with the moving belts, a couple which turns the former said cleats generally about said axes and causes them to fall to a short-side-down position.

7. Apparatus for uniformly orienting mitered-end cleats and feeding them short-side-down to a conveyor band of a box-part-making machine, said apparatus comprising a pair of movable orienting belts spaced apart a distance approximately equal to the length of said cleats for receiving said cleats aligned generally parallel to each other but of different orientation and conveying said cleats along a path generally at right angles to the long axes of said cleats, said orienting belts being inclined so as to present to the ends of said cleats surfaces extending upwardly and outwardly so that the cleats in a short-side-up position ride on said orienting belts at a higher level than the cleats in a short-side-down position, a cleat-turning member positioned above the path of said cleats at such level as to engage and impede forward movement of the upper portions of the cleats riding on said orienting belts in a short-side-up position but not the cleats riding in a short-side-down position, to create, with the moving belts, a couple which turns the former said cleats generally about said axes and causes them to fall to a short-side-down position, a movable cleat conveyor belt adapted to receive said cleats from said orienting belts and support all of said cleats at approximately the same level and convey them single file along a path generally lateral to said cleats, a cleat turning member positioned above said cleat conveyor belt to engage and impede forward movement of the upper portion of each of said cleats and create, with the moving cleat conveyor belt, a couple which rotates each of said cleats axially through a 90° angle in one direction, a hopper arranged above the conveyor of said box-part-making machine for holding a vertical stack of cleats in position for successive removal from said hopper by said conveyor band, and a guide channel arranged to conduct cleats

from said cleat conveyor belt to said hopper, said guide channel being shaped to turn said cleats axially through an angle of 90° in the opposite direction so that said cleats enter said hopper short-side-down.

8. Apparatus as claimed in claim 7 wherein each of said cleat turning elements is mounted for upward yielding movement to permit a cleat to pass thereunder while said cleat is rotating.

9. Apparatus for uniformly orienting mitered-end cleats and feeding them to a conveyor band of a box-part-making machine, said apparatus comprising a pair of movable orienting belts spaced apart a distance approximately equal to the length of said cleats for receiving said cleats aligned generally parallel to each other but of different orientation and conveying said cleats along a path generally at right angles to the long axes of said cleats by engagement of said orienting belts with the ends of said cleats, said orienting belts being inclined so as to present to the ends of said cleats surfaces extending upwardly and outwardly so that the cleats in a short-side-up position ride on said orienting belts at a higher level than the cleats in a short-side-down position, a cleat-turning member positioned above the path of said cleats at such level as to engage and impede forward movement of the upper portions of the cleats riding on said orienting belts in a short-side-up position but not the cleats riding in a short-side-down position, to create, with the moving belts, a couple which turns the former said cleats generally about said axes and causes them to fall to a short-side-down position, a conveyor adapted to receive said cleats from said orienting belts and to convey the same in single file along a path generally lateral to said cleats, a hopper arranged above the conveyor band of said box-part-making machine to receive said cleats from said cleat conveyor and hold them in position for successive removal from said hopper by said conveyor band, driving means for normally driving said orienting belts at a speed sufficient to supply cleats to said hopper at a rate slightly in excess of the rate at which they are removed from said hopper by said conveyor band, to cause a line of cleats to accumulate in said hopper and on said cleat conveyor, control means operable to disconnect said drive means from said orienting belts, said control means being responsive to the accumulation on said cleat conveyor of a substantially solid line of cleats of predetermined extent.

10. Apparatus for uniformly orienting mitered-end cleats and feeding them to a conveyor band of a box-part-making machine, said apparatus comprising a pair of movable orienting belts spaced apart a distance approximately equal to the length of said cleats for receiving said cleats aligned generally parallel to each other but of different orientation and conveying said cleats along a path generally at right angles to the long axes of said cleats by engagement of said orienting belts with the ends of said cleats, said orienting belts being inclined so as to present to the ends of said cleats surfaces extending upwardly and outwardly so that the cleats in a short-side-up position ride on said orienting belts at a higher level than the cleats in a short-side-down position, a cleat-turning member positioned above the path of said cleats at such level as to engage and impede forward movement of the upper portions of the cleats riding on said orienting belts in a short-side-up position but not the cleats riding in a short-side-down position, to create,

with the moving belts, a couple which turns the former said cleats generally about said axes and causes them to fall to a short-side-down position, a cleat conveyor adapted to receive said cleats from said orienting belts and to convey the same in single file along a path generally lateral to said cleats, a hopper arranged above the conveyor band of said box-part-making machine to receive said cleats from said cleat conveyor and hold them in position for successive removal from said hopper by said conveyor band, driving means for normally driving said orienting belts at a speed sufficient to supply cleats to said hopper at a rate slightly in excess of the rate at which they are removed from said hopper by said conveyor band, to cause a line of cleats to accumulate in said hopper and on said cleat conveyor, electrically actuated control means operable to disconnect said drive means from said orienting belts, said control means including at least two light transmitting means arranged at spaced positions on one side of the path of the cleats on said cleat conveyor, and arranged to direct beams of light through said path at spaced points, and photo-electric means mounted on the other side of said path in position to receive the beams of light from said light sources except when said beams of light are intercepted by cleats on said cleat conveyor, said photoelectric means being so connected to said control means that said photo-electric means actuates said control means to disconnect said drive means from said orienting belts only when the light beams from each of said light transmitting means to said photoelectric means are intercepted.

11. Apparatus as claimed in claim 10 wherein said light transmitting means are oriented to direct said beams of light across the path of the cleats at an oblique angle to the sides of said cleats.

12. Apparatus as claimed in claim 10 wherein said photo-electric means are sensitive to said beams of light through an area of greater lateral extent than the effective width of said cleats as viewed from the angle at which said beams of light cross the path of the cleats, so that said photo-electric means are effective to actuate said control means to disconnect said drive means from said movable belt means only if at least two adjacent cleats intercept each of said beams of light.

13. Apparatus for uniformly orienting mitered-end cleats and feeding them to a conveyor band of a box-part-making machine, said apparatus comprising a hopper for holding a supply of cleats aligned generally parallel to each other but of different orientation, a movable conveyor arranged below said hopper to receive said cleats from said hopper and convey them single file to a pickup position, a rotatable wheel having peripherally spaced elements for engaging said cleats at said pickup position and removing said cleats at intervals from said conveyor, a pair of movable orienting belts spaced apart a distance equal to the length of said cleats for receiving said cleats from said spacing wheel and conveying said cleats along a path generally at right angles to the long axes of said cleats, said orienting belts being inclined so as to present to the ends of said cleats surfaces extending upwardly and outwardly so that the cleats in a short-side-up position ride on said orienting belts at a higher level than the cleats in a short-side-down position, a cleat-turning member positioned above the path of said cleats at such level as to engage and impede forward movement of the upper por-

tions of the cleats riding on said orienting belts in a short-side-up position but not the cleats riding in a short-side-down position, to create, with the moving belts, a couple which turns the former said cleats generally about said axes and causes them to fall to a short-side-down position, a conveyor adapted to receive said cleats from said orienting belts and to convey the same in single file along a path generally lateral to said cleats, a hopper arranged above the conveyor band of said box-part-making machine to receive said cleats from said cleat conveyor and hold them in position for successive removal from said hopper by said conveyor band, driving means normally connected to drive the first said conveyor, 15 said spacing wheel, said orienting belts and said cleat conveyor, and control means operable to

disconnect said drive means from said spacing wheel and said orienting belts but to leave said drive means connected to said cleat conveyor, said control means being responsive to the accumulation on said cleat conveyor of a substantially solid line of cleats of predetermined extent.

DAVID G. KINGSLEY.
